UNITED STATES PATENT OFFICE.

CHARLES C. BADEAU, OF SCHENECTADY, NEW YORK.

ELECTRIC SWITCH.

SPECIFICATION forming part of Letters Patent No. 605,067, dated June 7, 1898.

Application filed September 17, 1897. Serial No. 651,983. (No model.)

To all whom it may concern:

Be it known that I, CHARLES C. BADEAU, a citizen of the United States, residing at Schenectady, in the county of Schenectady and State 5 of New York, have invented a certain new and useful Improvement in Electric Switches, of which the following is a specification.

The object of my invention is to produce a cheap and strong form of switch, one in which 10 the parts are readily attached to a large switchboard, such as are now commonly in use in electric-lighting plants.

My invention is illustrated in the accompanying drawings, in which—

15 Figure 1 is a side elevation, and Fig. 2 a top plan view, of one form of switch; and Fig. 3, a side elevation of a slightly-modified form.

Referring to the drawings, and more particularly to Figs. 1 and 2, A represents a switchboard, which is usually made of slate or marble, the switch members comprising a standard B, to which the movable switch-blades are pivoted, and a stationary contact- 25 plates B' and B².

C are the movable switch-blades.

The standard B and contact-plates B' and B² are cut from heavy strip metal and bent into L shape, and these parts are passed upward through the switchboard A, the opening for these parts being made by drilling a series of holes, as indicated in dotted lines at the left of Fig. 2.

D D are top plates provided with a slot 35 through which the standard B and contact-plates B' and B² are passed, and these plates are intended to cover the holes drilled in the switchboard A. The standard B and contact-plates are held in position by bolts E, 40 which are passed through holes in the plates D and screwed into the parts b of the standard and contact-plates. The bolts E are provided with nuts e for clamping the circuit- 45 terminals to the switch members. The movable switch-blades C are made in one piece of strip metal bent back upon itself, as shown in Fig. 2, the blade being provided with a wide loop at the bend, as shown at c. The blades are pivoted to the standard B by bolts 50 c', a spring-washer c² being provided between the blades and the bolt-heads. Intermediate

the two ends of the switch-blade a spacing-block C' of the same thickness as the parts B, B', and B² is firmly riveted in position.

In the drawings I have illustrated in Figs. 55 1 and 2 a double-pole double-throw switch, and Fig. 2 shows the two switch-blades connected together by a yoke F, of insulating material, to which the operating-handle G is secured. 60

In Fig. 3 the standard B and contact-plate B' are of the same form as those shown in Figs. 1 and 2, but instead of being passed through the switchboard A they are bolted to the front of the board by bolts passing 65 through the switchboard and screwing into the parts b. The heads of the bolts are preferably countersunk in the back of the switchboard. These bolts are also provided with nuts e, as in Fig. 1, for clamping the circuit- 70 terminals to the switch members.

With my improved form of switch no cast parts are employed and all machine-work is obviated, the various parts being cut from smooth strip metal of uniform width and 75 thickness, and hence requiring no finishing except the bending and drilling of holes. The parts are few and simple in construction, are readily and cheaply made, and can be quickly assembled on a switchboard. Furthermore, my improved form of switch-blade is well adapted for double-throw switches. 80

What I claim is—

1. In an electric switch, the combination of 85 a switchboard, stationary switch members secured to said board, a pivoted switch-blade cooperating with said switch members and made from a strip of metal bent lengthwise upon itself, and of substantially uniform width throughout, and a handle secured to 90 the switch-blade at the bend, substantially as herein specified.

2. In an electric switch, the combination of 95 a switchboard, stationary switch members bent into L shape and passed through holes in the switchboard and held in position by bolts screwed into the parts of the switch members underneath the switchboard, the bolts being provided with nuts for clamping circuit-terminal sto the parts of the switch members underneath the switchboard, a pivoted switch-blade made from a strip of metal 100

bent lengthwise upon itself, and a handle secured to the switch-blade at the bend, substantially as herein specified.

3. In an electric switch, the combination of 5 a switchboard, stationary switch members bent into L shape and passed through holes in the switchboard and held in position by bolts screwed into the parts of the switch members underneath the switchboard, the 10 bolts being provided with nuts for clamping circuit-terminals to the parts of the switch members underneath the switchboard, a pivoted switch-blade made from a strip of metal 15 bent lengthwise upon itself, and having a loop formed at the bend, and a handle secured to the switch-blade at the bend, substantially as herein specified.

4. In an electric switch, the combination of 20 a switchboard, stationary switch members bent into L shape and passed through holes in the switchboard and held in position by bolts screwed into the parts of the switch members underneath the switchboard, the 25 bolts being provided with nuts for clamping circuit-terminals to the parts of the switch members underneath the switchboard, a pivoted switch-blade made from a strip of metal

bent lengthwise upon itself, and having a loop formed at the bend, a spacing-block between the switch-blade, and a handle secured at the 30 bend, substantially as herein described.

5. In an electric switch, the combination of 35 a switchboard, L-shaped stationary switch members passed through a slot in the switchboard formed by drilling a series of holes, a slotted covering-plate for each stationary switch member for covering said holes and which plates are provided with bolt-holes, bolts passing through said plates and the switchboard and screwed into the parts of the 40 stationary switch members underneath the board whereby said members and the covering-plates are secured to the board, and a pivoted switch-blade made from a strip of metal 45 bent lengthwise upon itself, the two ends being pivoted to one of the stationary switch members, and having a handle secured to it at the bend, substantially as herein specified.

This specification signed and witnessed this 4th day of September, 1897.

CHAS. C. BADEAU.
